BOBBIN WINDING MACHINE

Brooks Marcellus, Rockford, Ill., assignor to Barber-Colman Company, Rockford, Ill., a corporation of Illinois

Application July 8, 1942, Serial No. 450,129

57 Claims. (Cl. 242—32)

1

The invention pertains to a machine for winding bobbins of the type employed in loom shuttles and commonly known as "cops" or "pirns."

The primary object of the invention is to provide a machine capable of producing filling-wound bobbins automatically at a rate substantially higher than has heretofore been possible.

A further object is to provide a bobbin winding machine embodying a series of winding units operating to produce a plurality of filling-wound bobbins simultaneously, with a driving and control mechanism of an advantageous character common to the several units.

A further object is to provide an automatic bobbin winding unit having a new and improved automatic donning and discharge mechanism.

Another object is to provide in such a machine an automatically operating bunch builder of improved construction in combination with a new and improved form of traversing device.

A further object is to provide a winding machine having various mechanisms to be operated automatically and in a predetermined timed relation, and an effectual control means governing the actuation of said mechanisms in proper sequence.

The objects of the invention thus generally stated, together with other and ancillary advantages, are obtained by the construction and arrangement shown by way of illustration in the accompanying drawings forming part hereof, in which:

Figure 1 is a fragmentary front view of a bobbin winding machine constructed in accordance with my invention and embodying a series of winding units arranged side-by-side.

Fig. 2 is a fragmentary plan view on a somewhat larger scale.

Fig. 3 is a transverse sectional view somewhat schematic in character and illustrating the arrangement of the major parts of each winding unit.

Fig. 4 is a fragmentary transverse sectional view taken approximately in the plane of line 4—4 of Fig. 1.

Fig. 4a is a fragmentary sectional view showing a portion of the gear train for driving the winding spindles.

Fig. 5 is an enlarged fragmentary sectional view transversely of the machine and showing the means employed in each unit to rotatably support the bobbins during the winding operation.

Fig. 6 is a fragmentary side elevational view

illustrating the yarn traversing device in association with each spindle.

Fig. 7 is a side elevational view of a bobbin and showing somewhat schematically the manner in which the yarn is wound thereon.

Fig. 8 is a fragmentary perspective view of a chuck for gripping the butt end of the bobbin.

Fig. 9 is a fragmentary vertical sectional view illustrating the manner in which the running strand is led from a suitably supported yarn mass to a bobbin being wound, and showing the parts in the position occupied during the winding operation.

Fig. 10 is a fragmentary front elevational view of the yarn supply mechanism.

Fig. 11 is a fragmentary horizontal sectional view further illustrating the means for controlling the running strand in its passage from the yarn mass to the bobbin.

Fig. 12 is a fragmentary front view of the device shown in Fig. 11.

Fig. 13 is a fragmentary perspective view illustrating more particularly an escapement mechanism controlling the release of bobbins one at a time from the empty-bobbin magazine, and the means for receiving and temporarily supporting the filling-wound bobbins until the new bobbin has been placed in position.

Fig. 14 is a front view of a bobbin magazine with parts broken away and other parts shown in section to illustrate the construction.

Fig. 15 is a fragmentary perspective view of a donning mechanism.

Fig. 16 is a plan view of a shearing and clamping device for seizing and holding the strand during the donning operation, parts being broken away to show the construction.

Fig. 17 is a fragmentary elevational view of the shearing and clamping device looking from the right in Fig. 16.

Fig. 18 is a fragmentary perspective view illustrating more especially a bunch building mechanism.

Fig. 19 is a fragmentary perspective view further illustrating a yarn positioning means.

Fig. 20 is a fragmentary sectional view showing the details of construction of the yarn clamp.

Fig. 21 is a fragmentary perspective view illustrating the mechanism for producing a feed or builder motion, and the means for controlling the starting and stopping of the machine.

Fig. 22 is a fragmentary end elevational view showing in particular the frame member at the right-hand end of the machine with its cover

removed to illustrate certain parts of the drive mechanism.

Fig. 22^a is a fragmentary sectional view substantially on line 22^a—22^a of Fig. 22 and showing a portion of the drive mechanism.

Fig. 23 is a fragmentary sectional view taken approximately in the line 23—23 of Fig. 22 and illustrating other details of the drive mechanism.

Fig. 24 is a fragmentary perspective view of a bobbin sorting and packaging means.

Fig. 25 is a schematic view illustrating the control means governing the operation of the machine.

Fig. 26 is a time chart of the main cam shaft of the control means.

The machine in general

In the preferred embodiment of my invention the machine comprises a plurality of winding units having a common drive and control mechanism whereby the several units operate to produce filling-wound bobbins simultaneously in each operating cycle of the machine. As shown the machine comprises an elongated horizontally disposed frame, and the individual winding units, of which ten are shown in the exemplary embodiment, are arranged side-by-side with the winding spindles disposed horizontally and extending transversely of the machine in laterally spaced relation as shown best in Fig. 2.

Referring now to Figs. 1 to 4, with particular reference to Fig. 3, each of the winding units comprises a bobbin holding means generally designated A for rotatably supporting the bobbins to be wound with yarn supplied from a yarn supply B. Below the spindle supporting means is a means C for receiving and temporarily supporting the wound bobbins after the same have been released from the holding means A. D designates an empty bobbin magazine having an escapement device controlling the successive release of empty bobbins onto an underlying empty-bobbin carrier or donning slide E. After a filled bobbin has been released from the winding spindle and deposited in the receptacle C, the donning slide E is advanced to introduce an empty bobbin into operative position relative to the winding spindle and as an incident thereto to clamp the strand extending from the source B to the filled bobbin. F designates generally a shearing and clamping device operated in the advance of the donning slide. As the yarn is being wound it is operated upon by a traversing device G. Preliminary to the initiation of the winding operation, the traversing device occupies a retracted position and at the beginning of the winding operation the thread is operated upon by an independent traversing device constituting a bunch builder H. From the receiving means C the filled bobbins are discharged downwardly and forwardly into pockets I by which they are arranged for final discharge into underlying containers J (Fig. 4).

The several winding units, together with the driving and control means for the various mechanisms, are embodied in a machine frame comprising a pair of end standards 1 and 2, upper and lower rear bars 3 and 3^a, (Fig. 4) and a pair of front angle bars 4 and 4^a, the latter being supported forwardly of the frame by end brackets 5 (Fig. 2). The end standards 1 and 2 are in the form of hollow castings forming chambers within which various parts of the driving and control mechanism are enclosed, the outer sides

of the chambers being closed by removable covers. Inasmuch as all of the winding units are alike in construction and operation, it is necessary to describe one only of these units following which the driving and control means for the machine will be described.

Bobbin holding means

10 Referring now to Figs. 2, 4 and 5, the bobbin supporting means A comprises a spindle 6 provided with a chuck 7 for receiving the butt end of bobbins 8 to be wound, and a tip holder or tail center 8 releasably supporting the tip end of the bobbin. The spindle (see Fig. 5) is suitably journaled in bearings provided in a tubular extension 9^a of a housing 9 stationarily supported upon the longitudinal frame member 3^a (Fig. 4). Upon the rear end of the spindle 6 is fixed a pinion 10 (Fig. 4^a) meshing with a spur gear 11 which in turn is driven from a drive shaft 12 extending longitudinally of the machine, this shaft being common to all of the units (Fig. 2). The housing 9 has a rear portion enclosing bevel gearing 13 on the shaft 12 and a short shaft 14, the latter being connected with the spur gear 11 by means of intermeshing gears 15.

15 The bobbin chuck 7 (Fig. 5) is of a construction adapted when the spindle is idle to receive freely the butt end of a bobbin and when in operation to grip the bobbin by the action of centrifugal force. As shown in Figs. 5 and 8, the chuck consists of a plurality of jaws formed on fingers 16 pivoted intermediate their ends at 17 upon a head 18 fast on the forward end of the spindle 6. The rear ends of the jaws are enlarged to form weights 19, and the arrangement is such that when the spindle is rotated at high speed the jaws will be swung inwardly from their pivots under the action of centrifugal force to grip firmly the butt end of a bobbin inserted between the jaws.

20 The tail center 8 comprises a cup-shaped member 20 shaped to receive the tip end of the bobbin and mounted for movement into and out of engagement with the bobbin in a direction generally axially thereof. The cup member is supported through the medium of antifriction bearings in the lower end of an arm 21 arranged for limited movement under the influence of a spring 22 relative to an arm 23 fast on the rock shaft 24 which extends longitudinally of the machine and is common to all of the units. Relative movement between the two arms by the spring 22 is limited by interengaging abutments 25 and 25^a. When the shaft 24 is rocked to carry the cup member 20 into engagement with the tip end of the bobbin, continuing movement of the shaft operates through the arm 23 to place the spring 22 under tension thereby holding the cup member 20 yieldably against the bobbin.

25 Rocking motion is imparted to the shaft by means of a disk cam 26 (Fig. 4) mounted on a main cam shaft 27 extending the full length of the machine and forming part of the control means common to the several units, the motion of the cam being transmitted to the rock shaft 24 through the medium of a follower lever 28, link 29 and arm 30, the latter fast on the shaft 24. The cam 26 is shaped so as to cause the tail center to occupy an elevated position upwardly and to the left of the position shown in Figs. 3 and 4 during the rearward movement of the empty bobbin by the donning slide as hereinafter set forth.

5
Yarn supply

Mounted upon the main frame above the winding spindles is a superstructure for supporting the yarn supply means B. This means comprises a series of yarn masses from which individual strands *s* are led downwardly to the various bobbins. As shown, the yarn masses are in the form of large conical packages *c* (Figs. 9 and 10) enclosed within individual housings *31*, the latter having open forward ends normally closed by covers *32* which are suitably apertured at *33* for the passage of the running strands. After passing over guide pins *34* disposed forwardly of the apertures *33*, the strands *s* continue downwardly through tensioning devices *35* and then over guiding elements *36* and *37* to the bobbin.

The yarn masses *c* are mounted upon suitable supports *38* carried by a channel bar *39* extending lengthwise of the machine and forming part of the superstructure, the housings *31* being also mounted upon said channel bar. At its opposite ends the bar *39* is supported upon a pair of standards *40* mounted upon the upper ends of the end members *1* and *2* of the main frame.

The cover *32* of each of the housings *31* is supported for independent raising and lowering movement and is yieldably held in either closed or open position. For this purpose, the cover is pivotally supported upon the forward ends of two parallel arms *41* and *42* pivoted respectively upon rods *43* and *44* extending the full length of the machine and mounted at their opposite ends in the standards *40*. Each of the covers has an upper end portion projecting when in its closed position above the casing and terminating in a tongue *32a* (Fig. 10). The arm *41* is pivotally connected to this tongue and the arm *42* has a yoke *42a* pivotally connected to the sides of the cover and shaped to encircle partially the rounded upper side of the casing. At its rear end, the lower arm *42* carries a counterweight *44a* to facilitate movement of the cover.

To hold the cover yieldably in either open or closed position, an overcenter device is employed. This device comprises a curved link *45* having one end connected by a contractile spring *46* to the channel rail *39* and the other end pivoted to the arm *41* above and forwardly of its pivotal axis *43*. The operation of the device in holding the cover either open or closed will be apparent from a comparison of the full and broken line positions shown in Fig. 9.

The aperture *33* provided in the cover for the passage of the strand has a rounded edge so as to avoid undue chafing upon the strand, and to facilitate threading of the strand through the aperture the cover plate is formed with a slot *46b* (Fig. 10) terminating at one end in the aperture and at its other end in a notch *46a* at the lower right-hand corner of the plate. Mounted forwardly of the aperture is the guide pin *34*. This pin is carried by a plate *47* extending forwardly from the cover plate.

The forwardly extending plate *47* provides a support for the tensioning device *35*. The latter (Figs. 1 and 9 to 12) consists of a grid composed of a plurality of fixed pins *48* and a series of intervening movable pins or fingers *49*, the latter mounted in suitable bearing heads *49a* to swing on an upright pivot pin *50* carried by a bracket *51* on the supporting plate *47*. The fingers *49* extend through slots *52* in the plate *47* and the pivotal ends of the fingers are acted upon by individual contractile springs *53* tending to swing

6

the fingers against a running strand bearing against the grid formed by the stationary pins *48*.

To facilitate threading of the strand through the tensioning device, a yoke *54* is mounted upon the pivot pin *50* and provided with a plurality of lugs *55*, one for each of the fingers *49*. These lugs are engageable with the supporting heads *49a* as shown clearly in Fig. 11 upon a swinging movement of the yoke in a clockwise direction. For convenience, the yoke is provided with a handle *56*. By movement of the handle the yoke is swung against the action of a spring *56a* from the full line position to the broken line position shown in Fig. 11. In this movement of the handle the fingers *49* are swung forwardly through an arc indicated by broken line positions, the foremost position being open or threading position. Upon release of the handle, the fingers *49* return to the full line position shown in said figure in which they are held by their individual springs in engagement with the running strand.

Lint produced in the passage of the yarn through the tensioning device is removed through the provision of an exhaust system comprising an exhaust chamber *57* for each of the tensioning devices and an exhaust trunk *58* extending lengthwise of the machine and connected with each of the chambers *57* by means of a flexible tube *59*. Each exhaust chamber *57* is formed in cooperation with the supporting plate *47* on the cover plate *32* by means of a member *57a* positioned on the side of the plate *47* opposite the pivot pin *50* and provided with slots *60* for the passage of the fingers *49*. The slots *60* are disposed adjacent the point of engagement of the running strand with the tensioning device, and the lint formed as an incident to the engagement of the strand with this device is drawn through these slots into the chamber *57* and thence by way of flexible tubes *59* to the exhaust trunk *58*.

After leaving the tensioning device, the running strand extends downwardly and rearwardly (Fig. 9) to the guide element *36* which is in the form of a pin carried by a suitable bracket *61* secured to and extending upwardly and forwardly from the upper longitudinal frame member *3*, the pin *36* being supported above the winding spindle and in a longitudinal plane disposed somewhat rearwardly of the chuck *7* on the forward end of the spindle. Finally the strand is led downwardly over the guide *37* to the bobbin being wound, or if no bobbin is in position, then to a point below the winding spindle where it is held in position to be seized in the next winding cycle as will presently appear.

Empty bobbin supply

The empty-bobbin magazines *D* are mounted forwardly of the winding spindles with their lower ends disposed somewhat above the horizontal plane containing the axes of the spindles; and operatively associated with each of the magazines is an escapement device controlling the release of the bobbins one at a time onto the underlying donning slide *E*. As shown in Figs. 2 and 13, each of the magazines comprises two side plates *62* and a back plate *63* cooperating to form a vertical channel adapted to receive and hold the stack of empty bobbins, the cross-sectional shape of the magazine conforming substantially to the lateral dimensions of the rear ends of the bobbins and the front of the magazines having a narrow slot *64* defined by the front edges of the plates *62* to permit passage of the forward

end portions of the bobbins. The magazines are supported in the present instance by means of brackets 65 mounted upon the longitudinal front frame member 4 with the lower end of the magazine spaced above the frame member to accommodate the donning slide E (see Fig. 14).

The escapement device for releasing the bobbins comprises a rectangular rocking frame 66 equipped with two pairs of bobbin engaging fingers 67, 67^a and 68, 68^a. The rear end portion of the frame straddles the lower end of the magazine and is pivoted to the bracket 65. The front end of said frame is pivoted on a bracket 69 carried by the front longitudinal frame member 4. The fingers 67 and 67^a are secured to one side of the frame and the fingers 68 and 68^a to the other side, the former being of a length to engage with the lowermost empty bobbin (Fig. 14) when the frame occupies its normal position, and the other fingers 68 and 68^a being somewhat shorter and adapted when the frame is rocked from its normal position to enter between the lowermost bobbin and the next succeeding bobbin.

The escapement frame normally occupies the position shown in Figs. 13 and 14, being held in this position by means of a contractile spring 70. To rock the frame for the purpose of releasing the lowermost bobbin, a bell crank 71 is pivoted in a suitable bearing on the bracket 65 and has one arm connected with the frame by means of a link 72 and its other arm pivoted to an actuating bar 73. The latter extends lengthwise of the machine, being common to all of the units, and is arranged for actuation by a cam 74 (Fig. 13) on the main cam shaft 27 and having a follower 75 fast on the rock shaft 76 extending transversely of the machine below the main frame member 4. The rock shaft carries at its forward end an arm 77 connected by a link 78 to the actuating bar 73. To prevent breakage of the parts in case any of the escapement fingers fail properly to clear the bobbins, the link 72 is preferably made compressible. As shown in Fig. 14 it consists of two telescoping parts 79 and 80 and a compression spring 81 operative in the movement of the actuating bar 73 and bell crank 71 to transmit a yieldable force to the rocking frame.

Donning slide

Upon the release of empty bobbins from the magazines D through the operation of their escapement devices, the bobbins drop onto underlying carriers on donning slides (Figs. 3 and 13). Each carrier is mounted for movement from a normal position beneath its magazine rearwardly to introduce the empty bobbin thereon into the chuck 7 of the spindle supporting means A preliminary to the movement of the tail center 8 by its cam 26 into holding engagement with the tip end of the bobbin. The bobbin carrier in the present instance comprises a bar 82 (Figs. 13 to 17) slidable in ways provided in the bracket 65 (Fig. 14). To one side of the bar 82 is fastened a plate 83 on which is mounted at spaced points a pair of upright members 84 and 85 (Fig. 15), one for supporting the tip end of the bobbin and the other the butt end thereof. The member 84 is in the form of an arm having its upper end notched slightly so as to form a recess for the bobbin. This arm is yieldably held in upright position by a spring 86 and interengaging stop means 87.

The other supporting member 85 is in the present instance in the form of a sheet metal stamping providing a pair of spaced fingers 88 con-

nected by a web 89 to form a yoke to receive the core of the bobbin adjacent the butt end thereof, the fingers being beveled to engage with the shoulders b' formed at the butt end of the bobbin (Fig. 3). The member 85 is pivotally mounted upon a block 90 secured to the slide plate 83 and is yieldably held in upright position by a torsion spring 91, the lower edge of the web 89 engaging the top of the block to limit movement of the member by this spring. To support the rear end of the slide, the bar 82 is extended as shown in Fig. 15, a suitable bearing therefor being provided on the gear housing 9.

To reciprocate the slide, an actuating arm 92 mounted upon a rock shaft 93 has its upper end pivotally connected to the slide bar 82. Said rock shaft is common to all of the units and on its extreme right-hand end (Fig. 22) it carries a cam follower 94 engaging with a cam 95 fast on the main cam shaft 27.

The bobbin carrying members 84 and 85 of the donning slide are yieldably mounted so as to permit return movement of the slide after the tail center 8 has been swung into its operating or holding position relative to the new bobbin. In the donning motion, this tail center is held by its cam 26 in an elevated or withdrawn position so that it does not interfere with the advance of the slide and the empty bobbin thereon. In order further to insure against damage to the parts, the actuating arm 92 is yieldably held in a predetermined position on the shaft 93 by means of a spring 96 acting to permit rocking motion of the shaft independently of the slide in the event that the latter should be interrupted in its donning movement. As seen in Fig. 15, the spring 96 normally tends to hold in interengagement with each other two abutments 97 and 98 respectively rigid with the actuating arm 92 and an arm 99 fast upon the rock shaft 93.

Fastening strand to new bobbin

Movable with the donning slide E is the means F adapted to position and hold the strand for engagement by the butt end of the empty bobbin as it is introduced into the chuck 7. In this connection, it will be understood that the strand is extended downwardly from the guide 37 for engagement by said device either by reason of its connection with the previously wound bobbin temporarily supported by the receptacle C or because of the action of a thread positioning device to be presently described.

The means provided for this purpose comprises in the present instance a plate 100 (Figs. 15, 16 and 17) secured to the underside of the block 90 and having an extended end with a V-shaped notch 101 therein. Fixed to the underside of this plate is a stationary blade 102 and a movable shearing and clamping blade 103, the latter being interposed between the blade 100 and the stationary blade 102. The parts are pressed together by means of a compression spring 104 surrounding a stud 105 which is anchored in the plate 100 (Fig. 17).

The movable blade 103 has rigid therewith an actuating arm 106 and positioned in the path of this finger so as to be engaged thereby in the movement of the donning slide is a stationary stop 107. As the slide advances the depending strand is positioned by the notch 101 and the shearing blade 103 actuated to sever the strand and at the same time clamp the same so as to hold it in the path of the butt end of the bobbin 75 as the latter is inserted into the chuck 7, thereby

binding the strand to the bobbin preliminary to the winding operation. As will be seen from Fig. 22, the cam 95 is so shaped that after a short dwell in its advanced position the donning slide is quickly returned to its initial or normal position beneath the empty-bobbin magazine C. Near the end of such return movement the actuating arm 106 of the shear blade 103 engages a second fixed stop 108 on the bracket 65 to open the shear preparatory to the next operating cycle.

Bunch builder

Before the main winding operation is started, it is desirable to form upon the bobbin at the 15 butt end thereof a small mass of yarn commonly termed a "bunch" for the purpose of facilitating detection in the loom shuttle of the approach of the end of the yarn supply on the shuttle. For this purpose I provide a bunch building mechanism adapted to wind a predetermined quantity of yarn onto the bobbin and including a special traverse effective only during this preliminary operation and adapted to control the lay of the 20 yarn whereby to insure the building up of a bunch of a size adequate for purposes of detection and yet avoid the winding of an unnecessarily large amount of yarn for this purpose.

Referring now to Fig. 18 of the drawings, this bunch building mechanism comprises a traversing pin 109 mounted on an arm 110 fast on a rock shaft 111. Loose on the shaft 111 is a slotted crank arm 112 constantly oscillated so long as the winding spindles are in operation by a cam 113 acting through a follower 114, rock shaft 115, arm 116 and link 117, the latter connected with the slotted arm 112.

Oscillatory motion imparted to the crank arm 112 is effective to rock the shaft 111 and thereby the pin 109 depending upon the position of an arm 118 pinned to the rock shaft and adapted to engage with an arm 119 rigid with the crank arm 112. This motion transmitting connection is effective only for the relatively short period of time required for bunch building. At such times the arm 118 is held against the arm 119 by the action of a torsion spring 120. At other times the arm 118 is moved out of the range of oscillation of the arm 119, by the action of a cam 121 on the main cam shaft 27. For this purpose the shaft 111 has loose thereon a spur pinion 122 meshing with a rack bar 123 to which is connected a follower 124 bearing on the cam 121 under the action of a contractile spring 125. The pinion 122 has a lost motion connection with the rock shaft 111 provided by an arm 126 rigid with the pinion and an arm 127 fast on the shaft.

In the relation of the parts shown in Fig. 18 the arms 118 and 119 are in abutting engagement so that the cam 113 is effective to oscillate the 60 traverse pin 109. When, however, the rack bar 123 is drawn downwardly by the cam 121, the lost motion in the connection between the pinion 122 and the rock shaft is taken up and the arm 127 then actuated to rock the shaft 111 sufficiently to remove the arm 118 thereon out of the range of oscillation of the arm 119 and at the same time swing the traverse pin 109 into an elevated inoperative position (Fig. 4).

The actuating cam 113 for the bunch building traverse is mounted upon a shaft 128 (Fig. 18) driven from the main drive shaft 12 by a speed reducing gear train 129. This gear train together with the cam and its follower are enclosed within a housing 130 (Figs. 2 and 4) providing bearings

5 for the shafts 115 and 128 and also for a shaft 128^a for certain of the idler gears of the train 129. The control cam 121 and its follower together with the rack bar 123 and its connection with the rock shaft 111 are suitably enclosed within the left-hand standard 1 of the main frame of the machine. It will be understood that the rock shaft 111 extends the full length of the machine and carries a traverse pin 109 for each of the units. As shown in Fig. 2, the torsion spring 120 is anchored to the right-hand frame standard 2.

Main traverse

Upon the completion of the bunch building operation, the main traversing devices G are advanced from normally inactive or retracted positions relative to the winding spindles into engagement with the running strands and thence advanced gradually with a feed motion in a direction axially of the spindles to cause the 25 yarn to be wound in successive layers shifting progressively to produce filling-wound bobbins. In the present instance, each of the units embodies its own traversing device, comprising principally a cylindrical cam 132 (Figs. 5 and 6) encircling the winding spindle and mounted for movement in a direction axially thereof. Said traverse cams form per se no part of the present invention, being the invention of Burt A. Peterson 30 as set forth in his copending application, Serial No. 428,993, filed January 31, 1942, now Patent No. 2,326,307, issued August 10, 1943. Briefly stated, each of said cams provides two oppositely sloping cam surfaces 133 and 134 moved successively into engagement with the running 35 strand as an incident to the continuous rotary motion of the cam. At a point immediately above each bobbin being wound, the strand is guided by a finger 135 (Fig. 9) acting to restrain the strand against lateral motion as the cam surfaces engage the same to shift it alternately in opposite directions on the axis of the bobbin. The finger 135 is mounted on the rail adjacent the traversing cam and somewhat below the 40 guide 37 which is mounted on a bracket 135^a.

The cams 132 for the several units are mounted upon a rail 136 (Fig. 21) extending the full length of the machine and having rigid with its opposite ends slide plates 137 guided in ways 138 formed on the inner sides of the end standards 1 and 2. The rail is of channel section except that at spaced points it is constructed to provide bearing blocks 139 in which the cams are rotatably mounted. In the present instance, each of the 45 cams has fixed on its rear end portion (Fig. 5) a bearing sleeve 140 supported in a bearing block 139 by an antifriction bearing 141. Suitable clamp means 142 is provided for removably securing the traverse cams in position in the bearing blocks 139.

Continuous rotary movement is imparted to the several traverse cams from a common drive shaft 143 (Fig. 2). For this purpose, worm gears 144 are fixed on the shaft 143 at spaced intervals corresponding to the lateral spacing of the units. Each of said gears meshes with a worm 145 rigid with a bearing sleeve 140. To enclose this worm gearing and to support the shaft 143, suitable 55 housings 146 are mounted upon each of the bearing blocks 139 of the channel rail 136.

During the winding operation a gradual feeding motion is imparted to the cam supporting rail 136 by means of a driven shaft 147 (Fig. 21); and at the end of the winding operation the feed 60 is interrupted and the rail is returned rapidly by

the action of a spring 148 under the control of a cam 149 on the cam shaft 27. The feed mechanism comprises spur pinions 150 fixed upon opposite ends of the shaft 147 and meshing respectively with the rack bars 151 on the slides 137. The right-hand end of the shaft 147 extends through the right frame standard 42 and has a disengageable driving connection with a source of power, consisting of a worm wheel 152 (Fig. 22) fast on the shaft and a driving worm 153 mounted for swinging movement into and out of engagement with the worm.

The torsion spring 148 is anchored at one end to one of the ways 138 and at its other end to the shaft 147 so that in the advancing movement of the rail the spring is placed under tension. The worm 153 is continuously driven during each winding cycle in a manner to be presently set forth, and is mounted upon a pivotal bracket 154 (Fig. 22) yieldably held by a spring 155 to maintain the worm in engagement with the worm wheel 152. To interrupt the feed of the rail, a cam 156 is provided on the cam shaft 27, which cam acts upon the follower arm 157 rigid with the bracket 154. Upon disengagement of the worm the rail is released to the action of the spring 148. Its return movement, however, is under the control of the cam 149 (Fig. 21) having a follower 158 fast on a rock shaft 159 and carrying an arm 160. The latter extends upwardly and rearwardly for engagement with a roller 161 mounted on one of the slides 137 through the medium of a plate 162 adjustably secured to said slide. By this arrangement, the traversing rail is returned rapidly to its initial position (shown in full lines in Fig. 5) but without shock or jar to the machine. Following such return, the worm drive for the rail advance mechanism continues to be held disengaged by the cam 156 until, in the next winding cycle, the bunch building operation has been completed, whereupon the cam 149 acts to impart a rapid forward movement to the traverse rail 136, advancing the traverse cams into operative position, substantially as shown in Fig. 6, whereupon the worm drive is reengaged.

Filled bobbin disposal

After the bobbins have been wound they are released from the holding means A and permitted to drop by gravity into the receptacles C. In these they are temporarily supported during the introduction into the holding means of empty bobbins to be wound in the succeeding cycle, such temporary support of the filled bobbins being for the purpose of continuing the running strands downwardly past the spindle chucks 7 so as to position them for engagement by the butt ends of the empty bobbins.

In the present instance the receptacles are in the form of troughs 163 (Figs. 4 and 13). Each of said troughs is pivotally mounted at its rear end upon a pin 163^a carried by a bracket 164 secured to the front face of the gear housing 9, the trough extending forwardly from the bracket in underlying relation to the bobbin being wound. The position of the trough 163 is controlled by a cam 165 fast on the cam shaft 27 and having a coacting follower 166 fixed on a rock shaft 167 extending lengthwise of the machine and common to the several units. Also mounted on the shaft 167 adjacent each of the troughs is an arm 168 connected by a link 169 with the trough at a point spaced a short distance forwardly of its pivotal axis. During the major portion of the

winding cycle the trough is maintained in horizontal position. It occupies this position upon the completion of the bobbin and its release from the holding means A.

Following the clamping and the shearing of the running strands in the advance of the donning slides, the cam 165 operates to tilt the troughs downwardly causing the discharge of the filled bobbins forwardly onto an inclined apron 170 (Fig. 4) and thence into a series of pockets 171 (Figs. 4 and 24) provided at the lower forward side of the machine. The pockets 171 are spaced apart longitudinally of the machine, there being one pocket for each winding unit (Fig. 1); and each pocket is adapted to receive and position the bobbin discharged by the corresponding trough 163 so that the bobbins will be disposed in a front to rear direction with the butt ends at the rear ends of the pockets. Moreover, the pockets are mounted for tilting movement above a series of compartments 172 (Fig. 24) into which the bobbins are finally deposited.

Referring now to Fig. 4, the pockets 171 are formed between the two parallel angle bars 173 and 173^a extending the full length of the machine and supported at opposite ends by cross bars 174 secured to and extending forwardly from the end standards 1 and 2. The vertical legs of the angle bars 173 and 173^a form respectively the front and rear walls of the pockets. Also, they provide bearings for the opposite ends of traverse rods 175 upon each of which is fixed a downwardly inclined plate 176 (Fig. 24) carrying an upright plate 177 to form a generally V-shaped bottom structure for the pocket.

The underlying compartments 172 are preferably formed in a plurality of conventional portable container units, each having one or more compartments therein. One such unit is herein shown in Fig. 24. It is suitably constructed of sheet metal to provide two separate compartments each underlying a pocket 171 and each having an inclined side plate 178 onto which the bobbins discharged from the pockets may slide in their passage to the bottom of the compartment. It has been found that this arrangement is advantageous in that it reduces handling of the bobbins thereby avoiding injury to the yarn and to the bobbins. Moreover, as finally disposed in the receptacle units, bobbins are properly arranged for convenient handling in the weave room.

Means is provided for automatically discharging the filled bobbins from the pockets 171. This means comprises (Figs. 13 and 24) a common actuating bar 179 operatively connected to the pivotally supported rods 175 by arms 180. The bar is reciprocated by a link and lever connection 181, 182 with the rock shaft 76 which serves, as hereinbefore described, to operate the escape mechanism of the empty-bobbin magazine. The arrangement is such that during each winding operation the bobbins wound in the previous operation are supported in the pocket 171 in convenient position for inspection by the attendant. Then in the conditioning of the mechanism for the next operation, the bobbins are discharged from the pockets into the compartments 172 below.

Strand positioning device

As hereinbefore described, the strands which are to be fastened to the bobbins at the beginning of a winding operation extend downwardly past the chucks 7 of the bobbin holding means A, usu-

ally to the previously wound bobbins which are temporarily supported in the holders 163. In case of breakage of any strand during the winding operation, it is obvious that some other means must be used for positioning the end of the strand leading to the yarn mass in the path of the notched plate 100 and its associated shear and clamping device. To this end, there is provided for each unit a thread positioning arm 183 carrying at its free end a thread clamp 184 normally disposed horizontally above the bobbin being wound, as shown in Fig. 4. The arms 183 are fast upon a rock shaft 185 extending length wise of the machine and are arranged in the present instance for actuation automatically through an operative connection with the mechanism controlling the bunch building traverse pin 109. This connection (Fig. 19) comprises a gear 186 fast on the shaft 185 and an idler gear 187 meshing with the gear 186 and with the pinion 122 which is operative in the reciprocation of rack bar 123 by the bunch building controlling cam 121 (see Fig. 18). The clamp 184 on the free end of each arm 183 may be of any suitable or preferred construction. As shown, it comprises a clamping member 188 fixed to the free end of the member 183 and carrying a stud 189 with an encircling spring 189^a yieldably holding a clamping member 190 against the member 188. The end portion of the arm 183 is offset so as to avoid interference between the strand and the arm.

In the event that a strand being wound becomes broken, the attendant simply fastens the same to the clamp 184. Then, in conditioning the mechanism for the succeeding cycle, the shaft 185 is rocked to carry the strand downwardly into the path of the notched plate 100 as the latter is advanced in the operation of the donning slide. When initially setting up the machine for a given series of winding operations, all of the strands will be fastened in the respective clamps 184 inasmuch as under such conditions no previously wound bobbins will be present in the holders 163.

Drive mechanism

Power for the operation of the winding spindles and the traverse and feed mechanisms is derived in the present instance from an electric motor M (Figs. 2, 4 and 25) having a flexible belt drive 191 (Fig. 4) with a short shaft 192 alined with the main drive shaft 12 and connected therewith by means of a combined clutch and brake unit. This unit is of a conventional form and comprises briefly a clutch 193 and a brake 194 arranged for operation selectively under the control of a shiftable collar 195. When the clutch is engaged, the shaft 12 is driven to actuate the winding spindles through the gear mechanisms enclosed within the housings 9 (Figs. 2 and 4). At the same time the cylindrical traverse cams are rotated by the longitudinal shaft 143 mounted upon the rail 136. This shaft 143 is driven from the main shaft 12. Thus, as shown in Fig. 2, said shaft 143 has a bevel pinion 196 thereon meshing with a bevel gear 197 having a splined connection with a shaft 198 suitably supported upon the right-hand frame standard 2. The rear end of the shaft 198 carries within a housing 199 a spur gear 200 (Fig. 23) meshing with a spur pinion 201 on a stub shaft 202^b having rigid therewith a spur gear 202^a. The latter meshes with a pinion 203^a on a stub shaft 202^b, the latter extending in a front to rear direction in the rear portion of the frame standard 2. A bevel gear 203 on the shaft 202^b meshes with a bevel gear 203^b on the main drive

shaft 12. For this purpose the latter also extends into the housing of the frame standard 2. Thus it will be seen that the power for imparting rotational movement to the traverse cams 136 is derived from the main drive shaft.

Also driven from the main drive shaft is the feed mechanism for advancing the traverse rail during each winding operation. As hereinbefore described, the feed rail drive shaft 147 has a disengageable worm drive 152, 153 (Fig. 22), the worm 153 being mounted for this purpose on a swingable bracket 154. For driving the worm the right end of the main drive shaft 12 has a spur pinion 204 thereon (Fig. 22) meshing with a spur gear 205 mounted together with a pinion 206 on a swingably adjustable arm 207 to accommodate pinions of different sizes for speed change purposes. The pinion 206 meshes with a spur gear 208 rigid with a bevel gear 209 (Fig. 25) driving a bevel gear 210 on a shaft 211, the latter carrying the worm 153.

Control mechanism

The operation of shifting the clutch 195 to start and stop the main drive shaft 12 is subject both to manual and automatic control. For this purpose a shifting yoke 212 (Fig. 21) is mounted upon the rear end of a rock shaft 213 extending in a front to rear direction near the left end of the machine and having an operating lever 214 at its forward end. A spring 215 tends to move the collar in a direction to disengage the clutch 193 and engage the brake 194. Rocking of the shaft against the action of the spring engages the clutch and at the same time swings an arm 216 thereon into engagement with a yieldable latch 217 whereby to hold the clutch engaged. The latch 217 is connected by a link 218 and arm 219 with a rock shaft 220 extending the full length of the machine and having operative levers 221 at conveniently spaced points for emergency operation. In case of stoppage of the machine through manual disengagement of the latch 216, 217, the machine may be restarted by operation of the hand lever 214.

The winding operation is normally interrupted automatically when the traverse rail reaches a predetermined forward position as determined by the completion of the bobbins being wound. For this purpose the latch 217 is disengaged from the arm 216 by means of a stop screw 222 engaging with a finger 223 rigid with the latch arm 217, said stop screw being mounted on a bracket 224 on the slide 137 (Figs. 21 and 25).

In order that successive winding operations may be performed automatically, power actuated means is provided for actuating the shifting collar 195 of the clutch and brake unit. For this purpose a cam 225 mounted on the main cam shaft 27 acts through a follower lever 226, link 227 and arm 228, to shift the yoke 212.

As soon as one group of bobbins has been filled the winding operation is interrupted and the cam shaft 27 set in motion to condition the parts for the next or succeeding operation. The cam shaft is separately driven by an electric motor M' (Fig. 22a) through the medium of a combined clutch and brake unit 231 and a gear train comprising a spur gear 27^a fast on the cam shaft (Fig. 4), a spur pinion 27^b, gear 27^c, and pinion 27^d. The latter is fast on a stub shaft extending through the standard 2 (Fig. 22) and carrying a spur gear 229 meshing with a pinion 229^a on the driven shaft 229^b of the clutch and brake unit 231.

The cam shaft motor M' (Fig. 25) is connected

in parallel with the main drive motor M and controlled by the hand switch 230. Interposed between the motor M' and the cam shaft 27 is the clutch and brake unit 231. This unit comprises a clutch 232, brake 233 and a shifting collar 234 arranged for actuation by a bell-crank 235. A spring 236 tends to shift the collar 234 in a direction to engage the brake 233. Movement of the lever 235 against the action of the spring is produced by means of a solenoid 237.

The cam shaft has two rest positions (Fig. 26). It occupies its No. 1 rest position when the machine is idle, being stopped in this position under the control of the attendant. The second or No. 2 rest position is occupied during each winding operation. For purposes of such control the solenoid 237 is arranged for energization by either of three switches, namely rail switch 238, feed switch 239 and cam switch 240, respectively connected in parallel circuits 241, 242 and 243.

The rail switch 238 is adapted to be closed by the slide 137 near the end of the forward travel of the traverse rail 136 or at the end of a winding operation. This energizes the solenoid and causes it to shift the collar 234 in a direction to disengage the brake and engage the clutch, whereby to start the cam shaft from its No. 2 rest position.

The feed switch 239 is open during the winding operation and closed as an incident to the disengagement of the feed for the traverse rail, through the operation of the worm supporting bracket 154 by the cam 158. This same circuit 242 has connected in series relation therein a plurality of hand switches 244 disposed at convenient points on the machine frame. If during a winding operation any one of the switches 244 has been opened by the attendant, the cam shaft will be stopped in its No. 1 rest position by the opening of switch 240 by cam 246 and this notwithstanding the closure of switch 239 by the disengagement of the feed mechanism.

The switch 240 is controlled by two stop cams 245, 246 on the cam disk. Stop cam 245 is effective to stop the cam shaft in the No. 2 or winding position because at this time both of switches 238 and 239 are opened. Stop cam 246 is effective to stop the cam shaft in its No. 1 position only if one of the switches 244 has been opened. Thus the switch 239, being closed upon the completion of each winding operation, constitutes a means for initiating a new winding operation.

Operation

Assuming that the machine is idle with the main switch 230 closed, if no previously wound bobbins are in position in the holders 163 (Figs. 3 and 4) the attendant threads the strand from the yarn masses c downwardly through the tensioning devices 35 and after passing the same over the guide pins 36 fastens the free ends of the strands in the clamps 184 of the thread positioning arms 183. Closure of the open hand switch 244 completes a circuit to the solenoid 237 through the feed switch 239, the latter being closed by reason of the disengagement at this time of the rail feed drive mechanism. The cam shaft is thus started from its No. 1 rest position.

Referring now to the time chart (Fig. 26), the donning slide of each of the units is moved rearwardly by the cam 95, rock shaft 93 and arm 92. Such rearward movement is indicated at 95^a in Fig. 26 and is immediately followed by a return movement indicated at 95^b. In its rearward movement the donning slide carries an empty

bobbin b previously dropped thereupon for movement into position in the holding means A.

In timed relation to the advance of the donning slide, the thread positioning arm 183 is swung downwardly as at 121^a by the cam 121 (Figs. 18 and 19) to position the strand for engagement in the notch 101 of the plate 100; or if a previously wound bobbin is in position in the underlying holder 163, then the strand positioning arm 183 merely makes an idle motion, the active strand leading to the bobbin in the holder 163 being engaged by said notch 101 in the advance of the slide. At a predetermined point in such advance, the shear operating finger 106 on the slide engages the stop 107 to cause the strand to be sheared and clamped.

During such movement of the donning slide of each unit, the tail center is actuated by cam 26 into engagement with the tip end of the bobbin as indicated at 26^a in Fig. 26. The butt end of the bobbin in its rearward movement with the donning slide has engaged the strand to be wound and the tail center in its final movement presses the bobbin into the chuck 1 with a yielding force, thereby firmly fastening the strand to the bobbin.

During the foregoing preliminary operation the traverse rail occupies a retracted position so that each of the traverse cams 132 is disposed out of the way of its corresponding bunch building traverse pin 109 which is now swung into its operative position under the control of the cam 121 as indicated at 121^a on the time chart. In this operation the rock shaft 111, carrying arm 110, and its traverse pin 109 is actuated by the spring 120 as permitted by the cam 121, the rack bar 123 moving upwardly to separate the stop arm 126 from the arm 127 as the arm 118 engages with the arm 119 for actuation thereby in the operation of the cam 113.

The bobbin receptacles 163 which up to this point have remained in horizontal position are now started downwardly by the cam 165 as indicated at 165^a to discharge any previously wound bobbins therein downwardly and forwardly over the apron 170 into positioning pockets 171. It will be observed that the bobbin receptacles are tilted downwardly during the return movement of the donning slides and following the gripping 50 of each strand to be wound by the butt end of the empty bobbin.

After the bunch traverse pins 109 have been swung downwardly into operative position, the main drive shaft 12 is set in motion for the purpose of rotating the winding spindles and the traverse cams, and also oscillating the bunch traverse pins. As indicated at 225^a, the clutch 193 of the combined clutch and brake unit for the main drive shaft is actuated by the cam 225 operating through follower lever 226 (Fig. 21), link 227 and yoke 212 to actuate the clutch and brake collar 195. The clutch is held in engagement by the latch 217, and as the spindles are revolved, the weighted jaws of the chucks 1 operate to grip firmly the butt ends of the empty bobbins.

With the starting of the drive shaft 12, the cam 113 of the bunch building mechanism operates to reciprocate the traverse pins 109, and while the cam is effective to oscillate the arm 112 so long as the drive shaft 12 is in motion, it continues to be effective to reciprocate the pins 109 for a short time only, the cam 113 being rendered ineffective by the cam 121 as indicated at 121^a in the time chart shortly before

the cam shaft reaches its No. 2 rest position.

At about the same time that the bunch traverse cam is rendered ineffective, the rail control cam 149 operates to advance the rail 136 rapidly a short distance as indicated at 149^a so as to position the traverse cams 132 into engagement with the running strands, whereupon the cam 156 operates as indicated at 156^a to swing the feed worm 153 into engagement with the worm wheel 152 thereby starting the feed rail forwardly so as to cause the cams to progress gradually along the axis of the bobbins being wound. The result is that, as each of the traverse cams is rotated and simultaneously advanced, the yarn is reciprocated along the axis of the bobbin so that the strand is wound in successive layers progressing gradually toward the tip end of the bobbin.

Just after the cam shaft leaves its No. 1 rest position, the cam 74 thereon operates as shown at 74^a to move the actuating bar 73 of the magazine escapement mechanism to the right in Fig. 13 thereby causing the rocker frame 66 to swing into the position shown in Fig. 13 whereby to position the fingers 67 and 67^a as shown in Fig. 14 and the fingers 68 and 68^a in position to release the bobbin onto the fingers 67 and 67^a. Thereupon the stop cam 245 moves into position to open the switch 240 as indicated at 245^a. At this time the rail switch 238 and the feed switch 239 are both open so that opening of the switch 240 deenergizes the solenoid 237 and the cam shaft comes to rest in its No. 2 position.

When the bobbins have been fully wound and the traverse rail has been advanced far enough to effect closure of the rail switch 238, solenoid 237 is reenergized to start the cam shaft from its No. 2 rest position. In the initial portion of such movement, a return stroke is imparted to the escapement actuating bar 73 as indicated at 74^b in the time chart, as a result of which the bobbin engaging fingers 67, 67^a and 68, 68^a operate to release the lowermost bobbin which drops by gravity onto the supporting members 84 and 85 of the donning slide. Also, the cams 149 and 156 operate, as indicated respectively at 149^b and 156^b, to advance the rail control arm 160 and disengage the worm feed. Motion of the arm 160 carries it into engagement with the roller 161 on the slide 137 and is followed by a return movement of the arm under the control of the cam 149 as indicated at 149^c. Thus, as an incident to the disengagement of the worm feed drive, the traverse rail is returned by the action of the spring 148 on the feed shaft 147 to its initial position with the traverse cams in retracted position in relation to the bobbins (Fig. 5), such return being under the control of the arm 160.

Closure of the switch 238 to start the cam shaft from its No. 2 rest position is accomplished by the traverse rail upon the completion of a winding operation. Thus in the approach of the traverse rail to the end of its forward movement, the latch 216, 217, is tripped to disengage the clutch 193 and engage the brake 194 whereby to stop the drive shaft and interrupt rotation of the winding spindles and the traverse cams. However, the parts are not brought to rest instantaneously and the movement of the rail as it coasts to a stop is utilized to close the rail switch 238 and start the cam shaft as above described. The tail center cam 26 operates to release the filled bobbins just as the cam shaft approaches its No. 1 rest position, the bobbins

dropping upon such release into their respective holders 163.

The cam shaft is stopped in its No. 1 position by the stop cam 246 opening switch 240 only in the event that the operator has so determined by opening one of the hand switches 244. This is for the reason that feed switch 239 has been closed by the disengagement of the worm drive. Thus a new cycle is initiated automatically in response to the interruption of the feed or builder motion subject to an interruption in the operation of the machine by the attendant opening any one of the hand switches 244.

I claim as my invention:

1. A bobbin winding machine having, in combination, bobbin holding means including a spindle rotatably supporting a bobbin to be wound, a traversing device, a support for said device mounted for movement in a direction axially of the spindle, means including a carrier for introducing empty bobbins into said holding means, power actuated means including a clutch for driving said spindle, said traversing device and said movable support, a power driven shaft having cam means for actuating said carrier and said clutch, disengageable latch means for holding said clutch engaged, means acting mechanically in the movement of said support at the end of a winding operation to disengage said latch means, and means adapted to initiate the operation of said cam shaft automatically in response to the movement of said support at the completion of the winding operation.

2. In a bobbin winding machine, a winding spindle, a traversing device, a drive shaft, a feed mechanism for moving said device axially of the spindle having a disengageable driving connection with said drive shaft, a spring tending to engage said connection, and a control mechanism including a cam shaft having means operative to effect the engagement of said connection by said spring to initiate the feed of the traversing device, means operative following the engagement of such connection to interrupt the rotation of the cam shaft, and means operative automatically in response to the completion of the winding operation to start said cam shaft and to disengage said connection.

3. A machine for winding bobbins comprising, in combination, means rotatably supporting a bobbin to be wound, a traversing device, a drive mechanism for rotating the bobbin and actuating said device, feed means for causing relative movement between said device and said bobbin axially of the latter, said feed means having a disengageable connection with said drive mechanism, and a cycle control mechanism operative to render said connection between the feed means and the drive mechanism effective at the beginning of the winding operation and ineffective upon the completion of the winding operation, said control mechanism further having cam means for effecting the return movement of said traversing device at a predetermined rate.

4. In a bobbin winding machine, a winding spindle, a traversing device having a normally retracted position relative to a bobbin supported by said spindle, a drive shaft, a feed mechanism for moving said device axially of the spindle having a disengageable connection with said drive shaft, and a control mechanism including a cam shaft having means operative to effect an initial advance of said device from its retracted position into engagement with the running strand and then to effect the engagement of said connection,

19

means operative following the engagement of such connection to interrupt the rotation of the cam shaft, and means operative automatically in response to the completion of the winding operation to start said cam shaft and to disengage said connection.

5. In a bobbin winding machine, a prime mover, a main drive shaft having a disengageable connection with said prime mover including a clutch and a spring tending to disengage the clutch, a winding spindle and a yarn traversing device operatively connected with the main drive shaft, a feed mechanism driven from said drive shaft and operative to impart a gradual feeding movement to said traversing device axially of the spindle, a latch for holding said clutch engaged against the action of said spring, and means operative automatically in the advance of said traversing device by said feed mechanism to disengage said latch, said feed mechanism having a disengageable connection with said drive shaft, cam means operative automatically upon the completion of one winding operation to interrupt the operation of the feed mechanism by the drive shaft, and means for returning said traversing device to its initial position.

6. In a bobbin winding machine, a winding spindle, a traversing device, power driven means including a drive shaft for actuating said spindle and said traversing device, a feed mechanism for imparting a gradual feeding motion to said device axially of the spindle, said feed mechanism having a disengageable driving connection with said drive shaft, and cam means operative upon the disengagement of said driving connection to govern the return movement of the traversing device at a predetermined rate.

7. In a bobbin winding machine, a winding spindle, a traversing device, power driven means including a drive shaft for actuating said spindle and said traversing device, a feed mechanism for imparting a gradual feeding motion to said device axially of the spindle, said feed mechanism having a disengageable driving connection with said drive shaft, a spring tensioned in the operation of said feed mechanism, and cam means operative automatically upon the completion of a winding operation to disengage said feed mechanism, said cam means further acting to govern the speed of return movement of the traversing device by said spring.

8. In a bobbin winding machine, a prime mover, a main drive shaft having a disengageable connection with said prime mover including a clutch and a spring tending to disengage the clutch, a winding mechanism actuated by said shaft and including a spindle, a yarn traversing device, and a feed mechanism for imparting a gradual feeding movement to said traversing device axially of the spindle, a control mechanism including a cam shaft, means on said cam shaft for engaging said clutch to initiate the operation of said winding mechanism, latch means operative upon the engagement of said clutch to hold it engaged against the action of said spring, and means operative upon the completion of the winding operation to release said latch and disengage the clutch.

9. A bobbin winding machine having, in combination, a winding mechanism comprising a spindle, drive means for said mechanism including a drive shaft, a prime mover and a combined clutch and brake unit, an operator for said clutch and brake unit, spring means acting on said operator normally tending to hold the brake en-

20

gaged and the clutch disengaged, cam means for actuating said operator, means including a latch for holding said clutch engaged, and means operable at a predetermined point in the winding operation to disengage said latch.

10. In a bobbin winding machine, a winding spindle, a traversing device having a normally retracted position relative to a bobbin supported by said spindle, a drive shaft, a feed mechanism for moving said device axially of the spindle having a disengageable connection with said drive shaft, and a control mechanism including a cam shaft having means operative to effect an initial advance of said device from its retracted position into engagement with the running strand and then to effect the engagement of said connection, means operative upon the engagement of such connection to interrupt the rotation of the cam shaft, and means operative automatically in response to the completion of the winding operation to start said cam shaft and to disengage said connection.

11. In a bobbin winding machine, a winding spindle, a traversing device having a normally retracted position relative to a bobbin supported by said spindle, a drive shaft, a feed mechanism for said device having a disengageable driving connection with said drive shaft, cam means operative to advance said traversing device from its retracted position into operative position relative to a running strand, and means operative at the end of such advance of the traversing device by said cam means to engage said feed mechanism.

12. In a bobbin winding machine, a winding spindle, a traversing device having a normally retracted position relative to a bobbin supported by said spindle, a drive shaft, a feed mechanism including a pair of relatively shiftable gear elements, and a control mechanism including a cam operative to effect an initial advance of said device from its retracted position into engagement with the running strand and another cam operative upon such initial advance to effect the engagement of said gear elements whereby to continue the operation of the feed mechanism.

13. In a bobbin winding machine, a winding spindle, a traversing device, power driven means including a drive shaft for actuating said spindle and said traversing device, a feed mechanism for imparting a gradual feeding motion to said device axially of the spindle, said feed mechanism having a disengageable driving connection with said drive shaft including a shiftable element, a cam shaft, and a cam on said shaft operative upon said element at a predetermined point in the advance of said device to disengage said feed mechanism.

14. A bobbin winding machine comprising, in combination, bobbin holding means including a spindle having a chuck for engaging the butt end of a bobbin to be wound, and a shiftable support for the tip end of the bobbin, a receptacle below the holding means adapted to receive a filled bobbin, an empty-bobbin carrier reciprocable from a position forwardly of said shiftable support into position beneath said holding means, said carrier having means supporting an empty bobbin including a device adapted to engage the core of the bobbin adjacent the butt end thereof whereby to carry said bobbin into said chuck as an incident to the rearward motion of the carrier, means operable in such rearward movement of the carrier to engage the running strand leading to the filled bobbin in said receptacle and position it for engagement by the butt end of the

21

bobbin as the latter is moved into said chuck, and means for actuating said carrier and said tip holder in timed relation to each other.

15. A bobbin winding machine comprising, in combination, a bobbin holding means including a spindle and a shiftable tail center, a receptacle below said holding means adapted to receive a filled bobbin, an empty-bobbin carrier reciprocable from a position forwardly of said holding means rearwardly to position an empty bobbin in said holding means operable in such rearward movement of said carrier to engage the running strand leading to a filled bobbin in said receptacle and position it for engagement by the butt end of the bobbin as the latter is moved into said holding means, and means for shifting said tail center out of the path of movement of the carrier during such rearward movement of the latter.

16. A bobbin winding machine comprising, in combination, a bobbin holding means including a spindle and a shiftable tail center, a receptacle below said holding means adapted to receive a filled bobbin, an empty-bobbin carrier reciprocable from a position forwardly of said holding means rearwardly to position an empty bobbin in said holding means, means operable in such rearward movement of said carrier to engage the running strand leading to a filled bobbin in said receptacle and position it for engagement by the butt end of the bobbin as the latter is moved into said holding means, and a control mechanism for reciprocating said carrier and for shifting said tail center out of the path of movement of the carrier.

17. A bobbin winding machine comprising, in combination, a bobbin holding means including a spindle and a shiftable tail center, a receptacle below said holding means adapted to receive a filled bobbin, an empty-bobbin carrier reciprocable from a position forwardly of said holding means rearwardly to position an empty bobbin in said holding means, and a control mechanism for reciprocating said carrier and for shifting said tail center out of the path of movement of the carrier.

18. A bobbin winding machine comprising, in combination, a bobbin holding means including a spindle and a shiftable tail center, an empty-bobbin carrier reciprocable in a position forwardly of said holding means rearwardly to position an empty bobbin in said holding means, and a control mechanism for reciprocating said carrier and for shifting said tail center out of the path of movement of the carrier and then rearwardly into engagement with the tip end of the bobbin, said bobbin carrier comprising an element for supporting the tip end of the bobbin yieldable relative to said tail center in the return movement of the carrier.

19. A bobbin winding machine having, in combination, bobbin holding means including a plurality of winding spindles supported in laterally spaced parallel relation and in a horizontal plane, a plurality of empty-bobbin magazines supported in upright position forwardly of said holding means, each of said magazines having an escapement device for releasing bobbins one at a time, empty-bobbin carriers normally positioned below the respective magazines and adapted to receive and support the empty bobbins released therefrom, an actuating bar common to said escapement devices, cam means for reciprocating said bar, and a yieldable motion-transmitting connection between said bar and each of said escapement devices.

22

20. In a bobbin winding machine, bobbin holding means comprising a horizontally disposed winding spindle having a chuck and a tip holder for engagement with the tip end of the bobbin and cooperating with said chuck to hold the bobbin being wound, an empty-bobbin carrier reciprocable from a position forwardly of said holding means to introduce an empty bobbin into the holding means, an upright magazine for supporting a stack of empty bobbins and open at its lower end, a frame mounted for rocking motion on an axis substantially parallel to the empty bobbins, fingers carried by said frame and operative in the rocking motion of the frame to release said bobbins one at a time onto said carrier, a cam shaft, and means on said cam shaft for operating said frame and said carrier in a predetermined timed relation to one another.

21. A bobbin winding machine having, in combination, bobbin holding means comprising a series of winding spindles disposed in spaced parallel relation with their axes in a common plane, each of said spindles having a chuck to be engaged by the butt end of a bobbin to be wound, a rock shaft extending transversely of the tip ends of the bobbins, tip holders on said rock shaft cooperating with the spindle chucks to hold the bobbins in winding position, empty-bobbin carriers mounted for reciprocation from a normal forward position into positions beneath said bobbin holding means, each of said carriers being operative in the rearward movement to position an empty bobbin into engagement with a spindle chuck, and means acting in timed relation to the movement of said carriers for rocking said shaft to carry said tip holders into and out of the paths of movement of the carriers.

22. A bobbin winding machine having, in combination, a series of winding spindles disposed in spaced parallel relation with their axes in a common plane, power driven means for rotating said spindles, each of said spindles having a chuck for engaging the butt end of a bobbin to be wound, a rock shaft extending transversely of the tip ends of the bobbins, cam means for imparting a predetermined rocking motion to said shaft, and a series of members on said shaft for supporting the tip ends of the bobbins, each of said members having a yieldable connection with said shaft, operative when the shaft is in active position to hold the member against a bobbin with a yieldable force.

23. A bobbin winding machine comprising, in combination, a winding spindle having a chuck for engaging the butt end of a bobbin to be wound, power driven means for rotating said spindle, a rock shaft, an arm loose on said rock shaft, a bobbin tip holder rotatably supported in said arm, a second arm fast on said rock shaft, said arms having interengageable abutments, and a spring connecting said arms and tending to hold said abutments into engagement with each other.

24. A bobbin winding machine comprising, in combination, bobbin holding means including a winding spindle having a chuck for receiving the butt end of a bobbin and a tip holder for engaging the tip end of a bobbin, a rock shaft carrying said tip holder with the latter depending from the shaft, an empty-bobbin carrier mounted for reciprocation from a forward position rearwardly to position an empty bobbin in said holding means, said bobbin carrier including a pair of supporting members thereon mounted to yield upon engagement with the tip holder in the return movement of the slide, and means actuating said rock shaft.

to move said tip holder out of the path of said members during the advance of said carrier.

25. A bobbin winding machine comprising, in combination, a bobbin holding means for rotatably supporting a bobbin to be wound, an empty-bobbin carrier reciprocable from a position forwardly of said holding means to position an empty bobbin in said holding means, a receptacle below the holding means for receiving a wound bobbin, a yarn supply, means on said carrier for shearing and clamping a strand leading to said supply and adapted to position the strand for engagement by the butt end of the empty bobbin in its movement into said holding means, and means for reciprocating said carrier operative to move said shearing means between said receptacle and an empty bobbin in said holding means, said shearing and clamping device being opened and closed in the reciprocation of said carrier.

26. A bobbin winding machine comprising, in combination, bobbin holding means for rotatably supporting a bobbin to be wound, an empty-bobbin carrier reciprocable from a position forwardly of said holding means, rearwardly to introduce an empty bobbin into said holding means, a receptacle below the holding means adapted to receive a filled bobbin discharged from the holding means, said receptacle being pivotally mounted at its rear end, and a control mechanism including a cam shaft having cam means thereon for actuating said carrier and said receptacle in a predetermined timed relation, the means for actuating said carrier comprising a cam on said cam shaft, a follower for said cam, and a yieldable motion transmitting connection between said follower and said carrier.

27. A bobbin winding machine comprising, in combination, bobbin holding means including a horizontal winding spindle, a traversing device movable axially of the spindle, a feed mechanism for said device, power driven means for actuating said spindle, said traversing device and said feed mechanism, an empty-bobbin carrier reciprocable relative to said spindle to introduce a bobbin into said holding means, a filled-bobbin receptacle disposed below said holding means and mounted for tilting movement to discharge the bobbin therefrom, a bobbin positioning pocket adapted to receive the filled bobbin discharged from said receptacle and also mounted for tilting movement to discharge the filled bobbin therefrom, a control mechanism governing the operation of said spindle, said traversing device and said feed mechanism by said power driven means, and a control means for said control mechanism operative to start the same at the end of a winding operation and to stop the same in a predetermined rest position, said mechanism being operative in its approach to said rest position to initiate a succeeding winding operation, means controlled by said mechanism operative preliminary to a winding operation to discharge a previously wound bobbin into said receptacle and from said receptacle into said pocket, and means operative at the end of said winding operation to discharge said filled bobbin from said pocket.

28. A bobbin winding machine comprising, in combination, bobbin holding means including a horizontal winding spindle, a filled-bobbin receptacle disposed below and adapted to receive filled bobbins released from said holding means, said receptacle being tilttable to discharge the

filled bobbins therefrom, a bobbin receiving and positioning pocket below and forward of said receptacle and mounted for tilting movement to discharge a filled bobbin therein, and cam means controlling the discharge of filled bobbins from said receptacle and said pocket.

29. A bobbin winding machine having, in combination, a winding spindle, power driven means for rotating said spindle, said spindle having a chuck for receiving and holding the butt end of a bobbin, a traversing cam having a retracted position rearwardly of said chuck, a feed mechanism for moving said traversing cam in a direction axially on the bobbin, a bobbin tip holder engageable with the tip end of the bobbin and cooperating with said chuck to support the bobbin, and cam means controlling said tip holder and said feed mechanism to cause the operation thereof in timed relation to each other.

30. A bobbin winding machine having, in combination, a winding spindle, power driven means for rotating said spindle, said spindle having a chuck, a cylindrical traversing cam having a retracted position encircling said spindle rearwardly of said chuck, and a feed mechanism for moving said cam axially of the chuck, said chuck having a diameter less than said cam and adapted to grip the butt end of a bobbin.

31. In a bobbin winding machine, a winding spindle, means coacting with said spindle to hold an empty bobbin to be wound, a main traversing means providing oppositely sloping cam surfaces engageable successively with the strand being wound, power driven means for rotating said spindle and imparting a continuous unidirectional movement to said traversing means to carry said cam surfaces across the path of the running strand, said cam means having an initial retracted position relative to the bobbin to be wound, and an auxiliary traversing means arranged for actuation by said power means in advance of the movement of the main traversing means into engagement with the running strand.

32. In a bobbin winding machine, a winding spindle, power driven means for rotating said spindle including a drive shaft, a bunch building mechanism including a traversing device, actuating means having a yieldable connection with said drive shaft for actuating said traversing device, and cam means for rendering said actuating means effective or ineffective.

33. In a bobbin winding machine, a winding spindle, power driven means for rotating said spindle including a drive shaft, a bunch building mechanism including a traversing device, a rock shaft, means driven by said drive shaft for actuating said rock shaft and including two abutting members yieldably held together, and cam means operative to disengage said members to render such connection ineffective.

34. In a bobbin winding machine, a winding spindle, power driven means for rotating said spindle, a traversing device, a rock shaft for actuating said device, a spring acting upon said shaft to move it in one direction, cam means driven by said power means for rocking said shaft against the action of said spring including a member loose on said shaft, a second member fast on said shaft, said spring tending to hold said members in engagement, and means for rocking said shaft against the action of said spring to separate said members whereby to render the operation of said device by the drive shaft ineffective.

35. In a bobbin winding machine, bobbin hold-

ing means comprising a winding spindle, a yarn supply, and means for guiding the yarn in its passage from said supply to said spindle, comprising a supporting bracket, a stationary grid comprising a plurality of spaced parallel pins mounted in said bracket, a plurality of fingers pivotally mounted on said bracket and yieldably held against a running strand passing over the pins of said grid, and means coacting with said bracket to form an exhaust chamber having an opening adjacent the point of engagement of the running strand with said grid and said fingers.

36. In a bobbin winding machine, a series of winding units arranged side-by-side and having bobbin holding means comprising a series of horizontally disposed laterally spaced winding spindles, an elongated supporting member extending horizontally above said units and transversely of said spindles, means on said supporting member adapted to support a plurality of yarn masses one for each unit, a series of housings enclosing the respective yarn masses and disposed side-by-side, the forward ends of said housings being open and having vertically shiftable covers each apertured for the passage of a running strand, each of said covers having a yarn tensioning device thereon, lint receiving and collecting chambers mounted on said covers adjacent said devices, an exhaust trunk, and a flexible connection between each of said chambers and said exhaust trunk.

37. In a bobbin winding machine, a series of winding units arranged side-by-side and having bobbin holding means comprising a series of horizontally disposed, laterally spaced winding spindles, an elongated supporting member extending horizontally above and transversely of said spindles, means on said supporting member adapted to support a plurality of yarn masses, one for each unit, a series of housings enclosing the respective yarn masses and disposed side-by-side, the forward ends of said housings being open and having vertically shiftable covers, each apertured for the passage of a running strand, means acting to counterbalance the weight of each of said covers, and spring means acting upon said covers to hold them in either open or closed positions.

38. In a bobbin winding machine, a series of winding units arranged side-by-side and having bobbin holding means comprising a series of horizontally disposed, laterally spaced winding spindles, an elongated supporting member extending horizontally above and transversely of said spindles, means on said supporting member adapted to support a plurality of yarn masses, one for each unit, a series of housings enclosing the respective yarn masses and disposed side-by-side, the forward ends of said housings being open and having vertically shiftable covers each apertured for the passage of a running strand, and guide means for the strand on each of said covers disposed forwardly of the aperture therein.

39. In a bobbin winding machine, a winding unit having a horizontal winding spindle, a stationary guide member above said spindle and a yarn supply mass mounted above said spindle, a housing enclosing said yarn mass and having an open forward side, a shiftable cover closing said open side and having an aperture therein for the running strand, and a guide on said cover over which the running strand passes to said stationary guide member.

40. A bobbin winder comprising, in combina-

tion, a winding mechanism including a spindle and a yarn traversing device, a main drive shaft, and means controlling the operation of said winding mechanism including a cam shaft, power drive means for said cam shaft including a control device, and electrically operated means for actuating said device, including a pair of independent control circuits, one of said circuits being effective when the winding mechanism is idle to cause operation of the cam shaft, and the other circuit being operative in the rotation of the cam shaft to stop it at the end of a given cycle after the initiation of a winding operation.

41. A bobbin winder comprising, in combination, a winding mechanism including a spindle and a yarn traversing device, a main drive shaft, and means controlling the operation of said winding mechanism including a cam shaft, power drive means for said cam shaft including a control device, and electrically operated means for actuating said device including a pair of independent control circuits, one of said circuits being effective at the end of the winding operation to start the cam shaft, and the other circuit being controlled by the cam shaft and operative to continue its operation through a predetermined cycle.

42. A bobbin winder comprising, in combination, a winding mechanism including a spindle, a yarn traversing device, and a feed means for effecting relative axial movement between the traversing device and the bobbin being wound, a main drive shaft, said feed means having a disengageable connection with said drive shaft, and means controlling the operation of said winding mechanism by said drive shaft including a cam shaft having means thereon controlling said disengageable connection for the feed means, drive means for said cam shaft, a device controlling the operation of the cam shaft by said drive means, and electrically operated means for actuating said device comprising three circuits connected in parallel, one of said circuits being rendered effective in response to the movement of the traversing device by said feed mechanism at the end of the winding operation, a second circuit effective when said feed mechanism is disengaged, and a third circuit operative at a predetermined point in the rotation of the cam shaft to interrupt the rotation thereof.

43. A bobbin winder comprising, in combination, a winding mechanism including a spindle, a yarn traversing device, and a feed means for effecting relative axial movement between the traversing device and the bobbin being wound, a main drive shaft, said feed means having a disengageable connection with said drive shaft, and means controlling the operation of said winding mechanism by said drive shaft including a cam shaft having means thereon controlling said disengageable connection for the feed means, drive means for said cam shaft, a device controlling the operation of the cam shaft by said drive means, and electrically operated means for actuating said device comprising three circuits connected in parallel, one of said circuits being rendered effective in response to the movement of the traversing device by said feed mechanism at the end of the winding operation, a second circuit effective when said feed mechanism is disengaged, and a third circuit operative at a predetermined point in the rotation of the cam shaft to interrupt the rotation thereof, said second circuit having a manually operable switch therein and said third circuit being operative under the

control of the cam shaft to stop the same at a second predetermined point in the event that the second circuit is rendered ineffective by said manual switch.

44. A bobbin winder comprising, in combination, a winding mechanism including a spindle, a yarn traversing device, and a feed means for effecting relative axial movement between the traversing device and the bobbin being wound, a main drive shaft, said feed means having a disengageable connection with said drive shaft, and means controlling the operation of said winding mechanism by said drive shaft including a cam shaft having means thereon controlling said disengageable connection for the feed means, drive means for said cam shaft, a device controlling the operation of the cam shaft by said drive means, and electrically operated means for actuating said device comprising a control circuit responsive to the advance of the traversing device to a predetermined point to initiate operation of the cam shaft, and a second circuit controlled by the cam shaft and effective to continue the movement thereof through a predetermined cycle.

45. A bobbin winding machine having, in combination, bobbin holding means including a spindle, power actuated means for driving said spindle, including a clutch, a traversing device, means driven by said power actuated means for effecting relative reciprocating movement between said traversing device and a bobbin mounted in said holding means, means controlling such relative reciprocation between the traversing device and the bobbin including a cam shaft, latch means for holding said clutch engaged, means acting mechanically upon the completion of a winding operation to disengage said latch means, and means on said cam shaft operable to reengage said latch means preliminary to a winding operation.

46. A bobbin winding machine having, in combination, a plurality of devices to be operated to condition the machine for winding, a cam shaft having a rest position and having a series of cams thereon for actuating said devices in a predetermined timed relation preparatory to a winding cycle, a motor for driving said shaft and a control mechanism for said shaft, including means operative in response to the completion of a winding cycle to start said shaft from its said rest position, means actuated by said shaft for stopping it in said rest position, and a combined manual and automatic means operative to interrupt said cam shaft upon the completion of a winding cycle.

47. In a winder, means for supporting a core of a package to be wound, means rotating said core, a traversing device providing thread guiding surfaces spaced from the core laterally thereof and movable unidirectionally transversely of the axis of the core, said device being initially disposed in a withdrawn position relative to one end of the core, and mechanism operative to effect first a short rapid relative positioning movement between said device and said core axially of the latter and then a slow relative feeding movement.

48. A bobbin winding machine having, in combination, a winding spindle, means on said spindle adapted to engage with the butt end of a bobbin to be wound, a support for said spindle, yarn traversing means comprising a hollow cylindrical member rotatively mounted coaxially of the spindle and having a cam surface operative in the unidirectional rotation of the member to im-

part a traversing movement to a strand being wound upon said bobbin, a support for said member, said supports having an initial relative position in which said cam surface is disposed in withdrawn position relative to the butt end of the bobbin, and means for effecting relative axial movement between said two supports operative to effect first a short rapid relative positioning movement and then a slow relative feeding movement.

49. A bobbin winding machine having, in combination, a winding spindle, means on said spindle adapted to engage with the butt end of the bobbin to be wound, a support for said spindle, yarn traversing means comprising a member operative to impart a traversing movement to a strand being wound upon said bobbin, a support for said member, said supports having an initial position in which said member is disposed in withdrawn position relative to the butt end of the bobbin, means for effecting relative axial feeding movement between said two supports during the winding operation, and cam means acting upon the completion of the winding operation to govern the restoration of the two supports to their initial positions.

50. A bobbin winding machine having, in combination, a winding spindle, means on said spindle for engaging with the butt end of the bobbin to be wound, a support for said spindle, yarn traversing means comprising a hollow cylindrical member rotatively mounted coaxially of the spindle and having a cam surface operative in the unidirectional rotation of the member to impart a traversing movement to a strand being wound upon the bobbin, a support for said member, said supports having an initial relative position in which said cam surface is disposed in withdrawn position relative to the butt end of the bobbin, a bunch building mechanism including an auxiliary traversing device, a feed mechanism effecting relative axial movement between said two supports, and means for actuating said auxiliary traversing device preliminary to the advance of the main traversing member from its withdrawn position into engagement with the running strand.

51. In a bobbin winding machine, a winding spindle and a support therefor, a traversing device also having a support, power driven means for rotating said spindle and said device, a shaft having an arm thereon operatively associated with one of said supports, and cam means imparting a rocking motion to said arm and operative to effect rapid relative movement between the supports in one direction.

52. In a bobbin winding machine, a winding spindle having a support, a traversing device also having a support, one of said supports being movable, power driven means for actuating said spindle and imparting a traversing movement to the movable support in a direction axially of the spindle, a control mechanism including a cam shaft, means operative upon the completion of a winding operation to start said cam shaft from a normal rest position, and means actuated by said cam shaft in such movement to effect the return movement of said movable support at a predetermined rate.

53. In a bobbin winding machine, a winding spindle having a support and a traversing device also having a support, one of said supports being movable, a power driven feed mechanism for the movable support, and a control mechanism operative at the beginning of a winding operation,

first to impart an initial advancing movement to said movable support and then to engage said feed mechanism to continue the movement of such support in the same direction, and means for stopping the control mechanism in a predetermined rest position upon the engagement of said feed mechanism.

54. In a bobbin winding machine, a winding spindle having a support, a traversing device and a support therefor, one of said supports being movable, a power driven disengageable feed mechanism for the movable support, and a control mechanism operative to engage said feed mechanism to impart movement to said movable support in one direction, means for stopping the control mechanism in a predetermined rest position upon the engagement of said feed mechanism, means operative upon the completion of the winding operation to start said control mechanism from said rest position, and means operative by said control mechanism when thus started to disengage said feed mechanism and cause the return of the support to its initial position.

55. In a bobbin winding machine, a winding spindle having a support, a traversing device also having a support, one of said supports being movable relative to the other, a power driven shaft, feed mechanism for moving one of said supports in a direction axially of the spindle including a gear element operatively associated with said power driven shaft and a second gear element operatively associated with the movable support and yieldably urged into driving engagement with said first gear element, and a control mechanism operative upon the completion of a winding oper-

ation to disengage said feed mechanism and cause the return of the support to its initial position.

56. In a bobbin winding machine having a winding spindle and a yarn traversing device, a drive shaft, a feed mechanism having a disengageable connection with said drive shaft for imparting movement to said traversing device axially of the spindle, a control mechanism including a cam shaft, means operative automatically at the end of the forward movement of the traversing device to stop said drive shaft and to start said cam shaft, means actuated by said cam shaft to disengage said driving connection whereby to interrupt the feed of the traversing device, and means including a cam on said cam shaft for effecting the return of the traversing device to its initial position at a predetermined rate.

57. A bobbin winding machine having, in combination, a winding mechanism comprising a spindle, a yarn traversing device and a support therefor movable axially of the spindle during the winding operation, drive means for said mechanism including a drive shaft, a prime mover and a first clutch, a control mechanism comprising a cam shaft, a prime mover and a second clutch, means acting at the end of the winding operation to disengage said first clutch, means operative in the coasting of said support following disengagement of the first clutch to effect engagement of the second clutch whereby to start said cam shaft, and means on said cam shaft operative to engage the first clutch to start said drive shaft and to reengage said disengageable driving connection successively.

BROOKS MARCELLUS.
